HUMIDIFYING UNIT WITH TUBE

Gottlieb R. Magney, Minneapolis, Minn.

Application February 18, 1932. Serial No. 593,794

16 Claims. (Cl. 257—138)

This invention relates to a humidifying device, and while the invention may have various applications, in the embodiment of the invention illustrated it is shown in connection with a radiator.

Great emphasis is being now placed by heating and ventilating engineers, on having an adequate supply of humidity in offices, homes and other dwelling rooms. It is desirable in order to evaporate a sufficient amount of water to supply the desired humidity, to have a water supply conduit and means for spraying the water in the form of a fine mist. It is also desirable to have heat to assist in evaporating the said mist and for this purpose the device of the invention is used in connection with a radiator. It is also desirable to have a small, compact and efficient unit as the humidifying means proper, which can be easily and inexpensively made, and which can be conveniently supported and disposed adjacent a radiator or within a casing enclosing said radiator.

It is an object of this invention, therefore, to provide a very simple and efficient unit adapted to be used for humidification, which unit is comparatively small, compact and one which can be readily disposed in the desired place or easily and quickly removed for inspection or other purposes.

It is a further object of the invention to provide a simple and efficient humidifying unit comprising an elongated casing having an opening extending along one side, members extending transversely across the opening having surfaces inclined to the axis of said unit, means for projecting a fine mist or spray longitudinally of said unit, said casing having one or more openings through which air may be directed thereto to engage said mist and pass out between said surfaces.

It is a further object of the invention to provide a humidifying structure comprising a radiator, a casing enclosing and extending above said radiator and forming a chamber above the radiator, a humidifying unit disposed in said chamber and extending longitudinally of the radiator and spaced therefrom, means extending through said chamber for supplying liquid to said unit, a nozzle at one end of said unit for directing a fine mist or spray thereto, said unit having openings in its bottom through which air rising from said radiator may pass to engage said mist and pass out between said surfaces.

Other objects comprise, in connection with the structure set forth, a conduit disposed in the radiator for heating the water supplied to said nozzle, means for controlling the discharge of water

from said nozzle, and a drain means leading from said unit.

These and other objects and advantages of the invention will be fully set forth in the following description made in connection with the accompanying drawings, in which like reference characters refer to similar parts throughout the several views, and in which:

Fig. 1 is a vertical longitudinal section through the casing enclosing a radiator and showing the invention applied thereto;

Fig. 2 is a central longitudinal section through the humidifying unit taken on line 2—2 of Fig. 1;

Fig. 3 is a vertical section taken on line 3—3 of Fig. 1;

Fig. 4 is a partial vertical section on line 2—2 of Fig. 1;

Fig. 5 is a vertical section showing the attachment to a heating coil in the radiator, Figs. 2 to 5 being shown on an enlarged scale;

Fig. 6 is a view similar to Fig. 1 showing the invention applied to a different type of radiator; and

Fig. 7 is a horizontal section on line 7—7 of Fig. 6.

Referring to the drawings, in Fig. 1 a radiator 10 is shown of the type commonly used for hot water or steam, the same comprising the spaced connected vertical sections 10a, the end sections being shown as having legs 10b for supporting the radiator. An inlet pipe 11 for the heating medium is connected to one end of the radiator, the same being controlled by a valve 12. The outlet pipe 13 is shown as connected to the opposite end of the radiator.

In accordance with the present invention, said radiator 10 is enclosed in a casing 14 and while this casing may be of various forms, in the embodiment of the invention illustrated it is shown as rectangular in horizontal and vertical cross section. Casing 14 is shown as having the hollow rectangular portion 14a extending thereabout which is supported upon corner legs 14b. Casing 14 has side and end walls and preferably has another rectangular portion or bead 14c about the top to give a decorated effect. Within casing 14 and spaced from the end walls thereof, are the supplemental end walls 14d extending from the top of casing 14 to a point adjacent the floor. The side walls of casing 14 preferably extend to a line adjacent the floor, thus providing an opening 14e. This opening permits the entrance of air into casing 14. The ends or partitions 14d are apertured to have the inlet and outlet pipes for the radiator pass therethrough. Casing 14 has an

opening 14f at its front side above radiator 10, which opening will extend for some distance across the front of said casing. A grid 14g preferably extends over this opening. 5 A humidifying unit designated generally as 16 is provided, and as shown in Fig. 1, the same is disposed in the chamber above radiator 10 formed by the casing 14. In the embodiment of the invention shown in Fig. 1, the member 16 is suspended from eyelets 17 secured in threaded blocks 18 preferably welded to the under side of the top of casing 14. Eyelets 17 are engaged by the hooks 19 and 20 secured to the unit 16. The unit 16 is also shown in Figs. 2, 3 and 4, and the same comprises an outer casing 16a shown as of elongated formation. While this casing may be of various forms, in the embodiment of the invention illustrated it is shown as somewhat tapered and thus in the form of a frustum of a cone. Casing 16a is closed by the end wall 16b having a cylindrical inwardly extending portion 16c disposed coaxially of casing 16a. A nozzle 21 is disposed in portion 16c and has its tip portion 21a projecting inwardly beyond portion 16c, the outer portion 25 of nozzle 21 having a shoulder abutting against the end wall 16b. Said nozzle has a chamber therein and tip 21a is interiorly threaded to receive an adjustable plug 21b, the end of which has radially extending small grooves at its end 30 cooperating with the small discharge aperture 21c of the nozzle. The outer portion of the nozzle has threaded thereto the liquid supply pipe 22. This pipe as shown in Fig. 1 extends to a solenoid valve 23 from which a pipe 24 extends to a strainer 25. Strainer 25 is connected by a suitable pipe 26 preferably containing a right and left coupling 27 to a heating conduit or coil 28 which extends into the radiator 10 as shown in Fig. 1. A plug 29 (see Fig. 5) is threaded into 40 the radiator and is itself bored and tapped to receive a pipe 26 as well as the coupling 27 to which the supply pipe 30 is connected. The supply pipe 30 will extend to a suitable source of water under pressure such as the city mains. The 45 ends of the heating conduit or coil 28 are also connected to the plug 29 by suitable couplings designated generally as 31.

The casing 16a has connected thereto by welding or otherwise, blocks 32 which are bored and 50 interiorly threaded. These blocks are adapted to receive the supporting hooks 20 for supporting the unit and certain of the blocks will be closed by plugs 33 when not in use. As shown in Figs. 1 and 4, the lower block 32 contains a 55 drain nipple 34 alined with an elbow 35 on a drain pipe 36, which drain pipe as shown in Fig. 1 will extend outside of casing 14 to any suitable drain connection. Pipe 36 can conveniently be supported from the radiator by a bracket 60 37 as shown in Fig. 1. The blocks 32 are disposed about casing 16a ninety degrees apart. Casing 16a also has three blocks 38 secured to the outside thereof, at its smaller end, which blocks are disposed ninety degrees apart and are bored and 65 interiorly threaded to receive the hook 19. It may be stated that the unit 16 may be supported in different positions and the blocks 32 and 38 are provided to accommodate all of these 70 positions. Casing 16a is closed at its smaller end by the end wall 16d. A disk-like plate 39 having a peripheral flange is secured to the inner side of the end wall 16d coaxial therewith and the smaller end of an inner casing 40 surrounds said peripheral flange and is secured 75 thereto to be supported thereby. Casing 40 is also in the shape of a frustum of a cone and has an open large end disposed somewhat adjacent end wall 16b, the inner end of nozzle 21 being located substantially at the end of casing 40. Casings 16a and 40 have openings 16e and 40a at one side, extending lengthwise thereof, these openings being alined in the two casings and said openings are spanned by a plurality of members 41 extending thereacross. The members 41 are in the shape of the segment of the frustum of a cone and the same have a slightly inturned flange 41a at their larger ends. Members 41 have their smaller ends directed towards the smaller end of casing 16a and at their ends engage and are connected to plates 43 which are parallel to the diametral plane extending centrally of the openings in casings 16a and 40. The plates 43 have one side extending along the outer side of casing 40 and secured thereto and their outer edge is bent at an angle and embraced by the folded end 16f of casing 16a extending along the side of opening 16e. A plate 40b extends across opening 16e at the larger end thereof and between casings 16a and 40. The member 41 at the larger end of the opening engages this plate 40b. Casing 16a has a plurality of openings 16g in its lower side, these openings being in the form of elongated slots with semi-circular ends. 80 85 90 95 100 105 110 115 120 125 130 135 140 145 150

A mercoid control member 44 has connected thereto a tube or casing 45 secured in and passing through a plug 46 in the end of the radiator opposite plug 29, said tube 45 extending some distance into the radiator and containing a thermostatic element. The mercoid control 44 is provided for regulating the solenoid valve 23 and will be suitably connected thereto. 105 110 115 120 125 130 135 140 145 150

In operation radiator 10 will be as usual provided with a heating medium and as stated, tube 30 will be connected to a source of water under pressure. The members 44 and 23 will be arranged so that upon the attainment of a certain temperature in the radiator, control member 44 will act to open the solenoid valve 23. The water from tube 30 will be heated in coil or tube 28 so as to be more readily evaporated and will pass through strainer 25 so as to be cleared of all solid matter. When said temperature has been attained, water can pass through the valve 23 and pipe 22 to the nozzle 21. Liquid is projected by nozzle 21 lengthwise of casings 16a and 40 in the form of a very fine mist. Air rising from radiator 10 passes into casing 16a through the openings 16g and thence to the open end of casing 40 and into said casing. The movement of the air into casing 40 will be induced and assisted by the spray from the nozzle 21. The warm air passing into casing 40 mixes with the finely divided liquid or mist sprayed thereto and a good portion of this liquid will be evaporated and pass with the air out between the plates 41. Some of the liquid projected in the form of mist will engage the conical surface of the plates 41 and as unit 16 including these plates will be heated by radiator 10, this liquid will be evaporated from said plates and will also pass out with the air through the openings between the plates 41. An effective mixing of the air and mist is thus obtained and the air passing out of casings 40 and 16a between plates 41 carries the desired amount of evaporated liquid. Any liquid not evaporated and carried out with the air will collect on the bottom of casing 40 at the inner side thereof and will drain to the large end of casing 40 and drop into the 150

large end of casing 16a as illustrated in Fig. 4. Any such liquid collecting in the larger end of casing 16a will pass out through the nipple 34 into the drain pipe 36 and will be carried away 5 to a suitable drain. The humidified air passing out of casing 16a or unit 16 will pass through the grid 14g and through opening 14f in casing 14 to the rooms to be humidified.

In Figs. 6 and 7 the unit 16 is shown as applied 10 to a radiator of the well known copper plate type. In these figures a casing 50 is shown similar to the casing 14, the same being mounted upon the legs 49. A radiator 51 is provided which is of the type comprising headers 51a between which 15 extend the tubes 51b. The tubes 51b carry a multiplicity of thin plates 52 of copper or other metal of high conductivity. The plates 52 are shown as being enclosed at the sides in thin metal casings 53. Coupling plugs 54 are threaded 20 into projecting hubs on the headers 51a and the inlet pipe 55 is connected with one of these plugs, the same having connected thereto the shut-off valve 56. The outlet pipe 57 connects with the other plug 54, the same having inserted 25 therein the trap 58. Supplemental end walls or partitions 59 extend from the top of casing 50 downwardly parallel therewith, said partitions terminating at the top of headers 51b and having flanges resting on said headers. The front 30 of casing 50 has an opening 50a therethrough adjacent its top and this opening preferably has a grid 50b therein. The side walls of casing 50 extend down in line with the top of legs 49 so that an opening is provided at the bottom of the 35 casing through which air may enter. A humidifying unit 16 shown in Fig. 1 is disposed in the chamber in casing 50 within the walls 59 and it will be noted that it is disposed with the members 41 and the openings 16e and 40a at the top instead of at the side as in Fig. 1. Rods 60 extend 40 across casing 50, being secured to the side walls thereof in any suitable manner and these rods are embraced by the hooks 20 and 19. A liquid supply pipe 61 is provided connecting with an 45 L-coupling 62 threaded into a plug 63. There is one of the plugs 63 threaded into the outer side of each of the headers 51a. A pipe extends between the plug 63 and through one of the radiator pipes 51b. The other plug 63 is connected 50 by pipe connections 65 to a strainer member 66, a right and left coupling 67 being inserted in the pipe 65. Strainer 66 is connected by the pipe connections 68 to a solenoid valve 69 which is in turn connected by a pipe 70 to the nozzle 21 of 55 unit 16. An elbow 71 is disposed beneath a drain nipple 34 and a drain pipe 72 leads from the nipple 71 to a suitable drain.

In operation heat will be supplied to the radiator 51 and the air in casing 50 particularly 60 within partitions 59 will be heated. The unit 16 will be brought substantially to the temperature in this chamber. The solenoid valve 69 will preferably be controlled by a humidistat in the rooms to be humidified. When the humidity falls to a certain point, valve 69 will be opened and when the humidity rises to a certain point, said valve will be closed. Said valve will, of course, be connected to the humidistat by suitable electrical conductors. Said valve could also 65 be connected to a thermostat in the rooms to be humidified so that it would not open unless the temperature in the rooms was at a certain point. Assuming that valve 69 is open, water will be supplied through tube 61 and will be heated in the 70 radiator 51. This water will pass through pipe 75

69 to strainer 66 and through valve 69 and pipe 70 to the nozzle 21. The liquid will be projected lengthwise of casings 16a and 40 as already described and the air rising through the openings 16g in the bottom of the unit 16 and will pass into the open end of casing 40. The air will commingle with the mist projected into said casing and a good portion of the liquid so projected will be evaporated and carried with the air out through the spaces between members 41. This air will pass out through the grid 50b into the room. As above set forth, any moisture which might strike or collect on the surfaces of members 41 will be evaporated and will pass out with the air. Should any moisture collect in casing 40, it will drain to the larger end thereof and into casing 16a and will pass out through drain nipple 34 into member 71 and through drain pipe 72. The water supplied to nozzle 21 will be heated in passing through radiator 51 so that it will be the more easily evaporated.

From the above description it is seen that applicant has provided a humidifying structure which can be easily and efficiently used in combination with a radiator or other heating unit. The humidifying unit is simple and compact and yet functions to supply a large amount of moisture to the places desired. The unit can be readily removed by simply disengaging the hooks which support it. The nozzle 21 can be withdrawn from the sleeve 16c and the unit is then entirely detached. It can very easily again be placed in operating position. The same is easily and inexpensively made and assembled.

It is possible in some places to use the device 105 without the outer casing 16a. The air then enters the large end of the casing 40 without first passing through the openings in the bottom of the casing 16a. When casing 16a is used, the air passing upwardly from the radiator passes through 110 the openings in casing 16a and a more uniform movement of the air is secured.

The device has been amply demonstrated in 115 actual practice and found to be very successful and efficient.

It will, of course, be understood that various changes may be made in the form, details, arrangement and proportions of the parts, without departing from the scope of applicant's invention, which generally stated, consists in a device 120 capable of carrying out the objects above set forth, in the parts and combinations of parts disclosed and defined in the appended claims.

What is claimed is:—

1. A humidifier structure having in combination, a casing closed at its ends, a second casing within and having a wall spaced from the wall of said first mentioned casing, said casings each having an opening along one side thereof, said openings being in alinement, a series of members extending across said openings having surfaces extending at an angle to the longitudinal axis of said second casing, means at one end of said first casing for projecting a fine spray of liquid or mist longitudinally thereof within said second casing, said first mentioned casing having openings therethrough at the bottom whereby air may pass therethrough into said second casing, mix with said mist and pass out between said surfaces.

2. A humidifying device having in combination, an elongated casing open at one end and having an opening extending along one side thereof, a plurality of spaced members extending across said last mentioned opening having surfaces of

- appreciable extent extending across and inclined at an appreciable angle to the longitudinal axis of said casing, means for directing a fine spray or mist into said casing lengthwise thereof, and 5 means for directing air into said casing whereby said mist and air commingle and pass out between said surfaces.
3. A humidifying device having in combination, a casing open at one end and having an opening 10 extending along one side thereof, members each in the shape of the segment of a frustum of a cone extending across said latter opening with their smaller ends directed toward one end of said casing, said members being spaced to leave openings therebetween, means for directing a fine spray or mist longitudinally of said casing toward said end, and means for directing air into said casing whereby said air will mix with said mist and pass out between said members.
- 20 4. The structure set forth in claim 3, said casing tapering toward one end and said members having their smaller ends directed toward the smaller end of said casing.
5. The structure set forth in claim 3, said members having a vertically disposed portion extending across the opening in the side of said casing and having vertically directed edges.
6. A humidifying device having in combination, a radiator, a casing enclosing said radiator and 30 forming a chamber thereabove, said casing having an opening leading from said chamber, a humidifying unit in said chamber above said radiator comprising a second casing extending longitudinally of said radiator, a liquid supplying conduit extending through said chamber to one end of said second casing, a nozzle secured to the end of said conduit for projecting a fine spray or mist into and longitudinally of said second casing, said 35 second casing having an outlet for air at one side and an inlet for air at its bottom above said radiator, whereby air rising from said radiator will pass into said second casing and out through the outlet opening thereof.
7. A humidifying device having in combination, 45 a radiator, a casing enclosing said radiator and forming a chamber thereabove, said casing having an opening leading from said chamber, a second casing in said chamber extending longitudinally of said radiator having closed ends, and an opening along one side, spaced members extending across said latter opening, a liquid conduit extending through said chamber to said second casing, a nozzle connected to said conduit for 50 projecting a fine spray or mist longitudinally of said second casing, said second casing having an opening spaced longitudinally thereof and of said radiator for air to pass thereinto, whereby air will rise from said radiator, pass into said second casing, commingle with said mist and pass out through the opening along the side of said second casing.
8. A humidifying device having in combination, 55 a radiator, a casing enclosing said radiator and forming a chamber thereabove, said casing having an opening leading from said chamber, a humidifying unit suspended in said chamber having an opening in the side directed toward the opening in said casing, said unit having a chamber therein, means for directing a fine spray or mist into 60 said chamber, said unit having an air inlet opening for said chamber disposed over said radiator to receive air rising therefrom and a drain means leading from said unit.
- 70 9. A humidifying structure having in combination, a radiator, a casing enclosing said radiator and forming a chamber thereabove, a humidifying unit supported in said chamber above the radiator, a liquid supplying conduit, a heating conduit in said radiator to which said conduit is connected, a conduit connecting said heating conduit and said unit, a nozzle connected to said last mentioned conduit for directing a fine spray or mist into said unit, and an inlet opening for said unit disposed over said radiator and outlet openings for said unit whereby air rising from said radiator will pass into said unit, engage said mist and pass out through said outlet openings. 80
10. A humidifying structure having in combination, a radiator, a casing enclosing said radiator and forming a chamber thereabove, said casing having an opening into said chamber at one side thereof, adjacent its upper end, a second casing within said chamber extending longitudinally of said radiator and having an opening extending along one side thereof, spaced members extending across said last mentioned opening and having surfaces inclined to the longitudinal axis of said second casing, means for projecting a finely divided spray or mist lengthwise of said second casing, said second casing having inlet openings in its portion above said radiator spaced longitudinally thereof, and of said radiator whereby air heated by said radiator passes into said second casing, engages said mist and passes out between said surfaces and then out through said first mentioned opening in said first mentioned casing. 90
11. A humidifying structure having in combination, a casing closed at its ends, having openings in its bottom and an opening extending along one side thereof, a second casing within said casing having an open end and an opening along one side aligned with said last mentioned opening, a series of spaced plates extending across said aligned opening forming transverse slots therebetween leading from said casings, means adjacent the ends of said casings for directing a finely divided spray or mist lengthwise of said casing into the open end of said second casing whereby air can pass into the bottom of said first mentioned casing into the end of said second mentioned casing where it may engage said mist and pass out through said slots. 100
12. A humidifying structure having in combination, a casing having one end open and having an opening extending along one side thereof, said latter opening being of considerable width, spaced plates secured to said casing and extending transversely across said opening and having inner surfaces inclined inwardly and toward one end of said casing, means adjacent the other end of said casing for projecting a fine mist thereinto, said casing being open at said other end for the entrance of air whereby said air will engage said mist and pass out between said spaced plates. 110
13. A humidifying structure having in combination, a casing having one end closed and one end open, said casing having an opening of considerable width extending lengthwise thereof for the greater portion of its length, a second casing surrounding and spaced from said casing having closed ends and having an opening extending along the side thereof aligned with the opening extending along the side of said first mentioned casing, spaced plates extending along the sides of said aligned openings and between the walls of said casings, a plurality of spaced plates extending transversely of said openings and having inner surfaces directed inwardly and toward one end of said casing, said outer casing having 120
14. A humidifying structure having in combination, a radiator, a casing enclosing said radiator and forming a chamber thereabove, said casing having an opening leading from said chamber, a humidifying unit suspended in said chamber having an opening in the side directed toward the opening in said casing, said unit having a chamber therein, means for directing a fine spray or mist into said chamber, said unit having an air inlet opening for said chamber disposed over said radiator to receive air rising therefrom and a drain means leading from said unit. 130
15. A humidifying structure having in combination, a radiator, a casing enclosing said radiator and forming a chamber thereabove, a humidifying unit supported in said chamber above the radiator, a liquid supplying conduit, a heating conduit in said radiator to which said conduit is connected, a conduit connecting said heating conduit and said unit, a nozzle connected to said last mentioned conduit for directing a fine spray or mist into said unit, and an inlet opening for said unit disposed over said radiator and outlet openings for said unit whereby air rising from said radiator will pass into said unit, engage said mist and pass out through said outlet openings. 140
16. A humidifying structure having in combination, a radiator, a casing enclosing said radiator and forming a chamber thereabove, a humidifying unit supported in said chamber above the radiator, a liquid supplying conduit, a heating conduit in said radiator to which said conduit is connected, a conduit connecting said heating conduit and said unit, a nozzle connected to said last mentioned conduit for directing a fine spray or mist into said unit, and an inlet opening for said unit disposed over said radiator and outlet openings for said unit whereby air rising from said radiator will pass into said unit, engage said mist and pass out through said outlet openings. 150

air inlet openings in its bottom side and means for projecting a fine liquid mist into said inner casing.

14. A humidifying structure having in combination, a casing having an open end and an opening along one side thereof, members extending across said opening having surfaces inclined inwardly and downwardly toward the end of said casing opposite said open end, said members being spaced to form louvers therebetween, means for supporting said casing adjacent a heating means, and means adjacent the open end of said casing for directing a fine spray or mist into said open end whereby air will be drawn into said casing and will pass out through said louvers.

15. A humidifying structure having in combination with a radiator, a housing enclosing said radiator having an opening along one side thereof, an elongated casing in said housing above said radiator, said casing being open at one end for the entrance of air, a nozzle disposed at said open

end of said casing for directing a fine spray of mist into said casing lengthwise thereof, said casing and air being heated by said radiator and said casing having a discharge opening disposed adjacent said opening in said housing.

16. A humidifying unit having in combination, an elongated casing adapted to be supported over a radiator having an air inlet opening and an outlet opening spaced from said inlet opening, means adjacent one end of said casing disposed substantially axially thereof for projecting a finely divided spray or mist lengthwise of said casing, and a plurality of spaced plate-like members extending across said outlet opening and a drain means leading from said casing whereby heated air rising from said radiator will pass into said inlet opening through said spray, between said plates, and out at said outlet opening.
